(57) **CLAIM**

The ornamental design for a cosmetic box, as shown and described.

DESCRIPTION

FIG. 1 is a perspective view of a first embodiment of a cosmetic box showing the new design, the cosmetic box being shown in a closed state;

FIG. 2 is a front view thereof;

FIG. 3 is a back view thereof;

FIG. 4 is a side view thereof;

FIG. 5 is a side view thereof;

FIG. 6 is an end view thereof;

FIG. 7 is an end view thereof;

FIG. 8 is another perspective view of the cosmetic box of FIG. 1 shown in a partially open state, revealing the insert feature;

FIG. 9 is another perspective view thereof, shown in an open state, and showing the insert feature removed and partially open;

FIG. 10 is a top plan view of the insert feature thereof, shown in a flattened state, and shown separately from the cosmetic box to show aspects of the design not visible when combined;

FIG. 11 is a perspective view of a second embodiment of a cosmetic box showing the new design, the cosmetic box being shown in a closed state;

FIG. 12 is a front view thereof;

FIG. 13 is a back view thereof;

FIG. 14 is a side view thereof;

FIG. 15 is a side view thereof;

FIG. 16 is an end view thereof;

FIG. 17 is an end view thereof;

FIG. 18 is another perspective view of the cosmetic box of FIG. 11 shown in a partially open state, revealing the insert feature;

FIG. 19 is another perspective view thereof, shown in an open state, and showing the insert feature removed and partially open; and,

FIG. 20 is a top plan view of the insert feature thereof, shown in a flattened state, and shown separately from the cosmetic box to show aspects of the design not visible when combined.

(Continued)

The broken lines are shown for the purpose of illustrating parts of the article that form no part of the claimed design.
